UNITED STATES PATENT OFFICE

WALTON B. ROBE, OF TOWSON, MARYLAND

MOLD

Application filed July 6, 1928. Serial No. 290,822.

My invention relates to improvements in molds.

The object of my invention is to provide a mold and chill for molding hollow or solid 5 castings having depressions therein provided with means for supporting the hot chills so that they do not come in contact with the green sand, whereby the pattern is not injured by the formation of steam and the accumulation of moisture on the casting is also prevented.

Another object of my invention is to provide an improved chill made in sections and so supported that it can expand and contract 15 under the intense heat to which it is subjected, and yet will not materially affect the contour of the depression formed in the casting.

A further object of my invention is to provide a mold of this character in which the 20 drag and cope are, in their usual manner, assembled with the chills in their proper position so that the desired casting can be molded.

A still further object of my invention is to 25 provide a simple, cheap and effective mold to accomplish the above results and having certain details of structure and combination of parts hereinafter more fully set forth.

In the accompanying drawings:

30 Figure 1 is a longitudinal vertical sectional view of a mold showing a hollow casting formed therein.

Figure 2 is a top plan view of the drag.

35 Figure 3 is a bottom plan view of the casting shown in section, in Figure 1.

Figure 4 is a transverse vertical sectional view taken on the line 4—4 of Figure 1.

Figure 5 is a top plan view of one of the chills.

40 Figure 6 is a transverse vertical sectional view of one of the chills taken at right angles to that shown in Figure 4.

Figure 7 is an enlarged sectional view 45 showing the shape of the baked sand core for forming the openings in the bottom of the casting.

Figure 8 is a top plan view of a modified form of chill in which the springs shown in Figure 6 are dispensed with.

50 Figure 9 is an end elevation of Figure 8.

In the drawings, I have shown my improved mold particularly adapted to cast hollow cylinder heads having depressions there-in forming compression chambers, but it will be understood that the same mold can be used 55 to mold any form of casting in which it is desired to form hollow depressions.

Referring now to the drawings, 1 represents the drag which, as shown, is of a hollow box like form, having arranged in the 60 bottom thereof any number of cup shaped members 2, having their upper ends in a horizontal plane with the upper end of the drag. The cup shaped members are of any 65 desired shape according to the shape of the depressions desired to be formed in the casting. As shown, they are of an elongated tapering form having curved ends which correspond with the shape of the ordinary compression chamber in a cylinder head.

In the drawings, I have shown four of the 70 cup shaped members 2, and therefore, in the illustration I am showing a cylinder head for a four cylinder engine, but it will be understood that any desired number of chills can 75 be used according to the number of cylinders.

In assembling the mold for operation, green sand 3 is placed in the drag around the cup shaped members 2, and leveled off 80 even with the upper end of the cup shaped members and with the upper end of the drag. The chills 4 are placed upon the upper ends of the cup shaped members 2, and these chills are of a contour exactly the shape of 85 the cup shaped members, and therefore the chills do not engage the green sand 3 in the drag.

The chills are preferably made in three sections 5, 6 and 7, the sections 6 and 7 having oblique contacting surfaces 8 and 9, and the section 5 having an oblique contacting surface 10 engaging the oblique contacting surfaces 11 of the sections 6 and 7. Arranged below the three sections of the chills is a plate 12 having three openings 13, 14, 90 and 15 through which the bolts 16, 17 and 18 pass, and these bolts, as shown, are of a diameter less than the openings for a purpose hereinafter more fully described. The 95 bolts are provided with heads 19 and sur- 100

rounding the bolts are coil springs 20 which engage the lower face of the plate 12 and the heads of the bolts 19 and normally holding the three sections 5, 6 and 7 of the chills down upon the plate 12, as shown in the drawings.

In casting a hollow cylinder head the core 21 of baked sand is formed of the shape shown in Figures 1 and 4 of the drawings, and said baked sand core is provided adjacent each end with small projections 22 which rest upon the sand 3 in the drag. The cope 22' is of the usual construction and is filled with green sand 23, and has the pattern 24 formed therein to correspond with the shape of the upper outer face of the cylinder head. The usual gate 25 is employed for pouring the molten metal to the casting and the riser 26 arranged at the opposite end to allow any gases and foreign matter in the mold to pass upwardly therein, whereby a more perfect casting is produced, all of which is well understood and needs no further description. The drag 1 and cope 22' are secured together by means of bolts 28 of the usual form passing through the ears 27 and 27' carried by the cope and drag. In casting a cylinder head of the type shown in Figure 1 of the drawings it will be noted that before the parts are assembled as shown in Figure 1 the chills are heated to a very high degree, and as the molten metal is poured through the gate 25 it fills the mold, and coming in contact with the highly heated chills, the chills are still further heated and the heat will expand the metal thereof, causing the obliquely engaging faces to slightly ride one upon the other against the tension of the spring 20, and thus slightly increase the size, but not to any material noticeable degree. After the metal has solidified, the cope is removed and by this time the chills have slightly cooled so that the springs 20 will draw the sections 5, 6 and 7 back to the position shown in Figures 4, 5 and 6 in the drawings, away from the casting, whereby the casting is readily removed, leaving the chills in the position for another molding operation. The baked sand core 21 is then removed from the mold in the usual manner and a cylinder head is produced having the four compression chambers 27, 28, 29 and 30. The projections 22 of the baked sand core are in the four openings 31, 32, 33 and 34, which are adapted to communicate with the water jacket of the cylinders. The projection 35 at the end of the casting is for the purpose of connecting the hose to the water circulating system of the engine.

As heretofore stated, I have shown a mold for molding cylinder heads, but it will be understood that I do not care to limit myself to the same, as the broad invention is in supporting the hot chills on the cup shaped members so that they do not engage the green sand of the drag, and thus prevent the forma-

tion of any steam or moisture on the casting.

Having thus fully described my invention what I claim is:—

1. A mold comprising a drag, hollow chill supporting members in said drag, and chills resting upon the upper ends of the chill supporting members.

2. A mold comprising a drag, hollow chill supporting members in said drag, and chills of the same contour as the upper ends of the supporting members and resting thereon.

3. A mold comprising a drag, hollow chill supporting members in said drag, and having their upper ends flush with the upper edge of the drag, and chills resting upon the upper ends of the chill supporting members.

4. A mold comprising a drag, hollow chill supporting members in said drag and having their upper ends in a plane with the upper edge of the drag, and the space between the chill supporting members filled with sand, and chills resting upon the upper ends of the chill supporting members.

5. A mold comprising a drag, hollow chill supporting members in said drag, and expansible chills resting upon the upper ends of the chill supporting members.

6. A mold comprising a drag, hollow chill supporting members in said drag and having their upper ends in a plane with the upper edge of the drag, and the space between the members filled with green sand, and expansible chills resting upon the upper edge of the chill supporting members.

7. A mold comprising a drag, hollow chill supporting members in said drag, and expansible chills of the same contour as the upper ends of the chill supporting members and resting thereon.

8. A mold comprising a drag, hollow chill supporting members in said drag, chills resting upon the upper ends of the chill supporting members, a baked sand core above the chills, and a cope having a mold formed therein above the baked sand core by a pattern.

9. A mold comprising a drag, chill supporting members in said drag, the spaces between the chill supporting members filled with green sand, chills supported by the upper ends of the chill supporting members, a baked sand core resting upon the green sand, and a cope having a mold cavity above the baked sand core formed by a pattern.

10. A mold comprising a drag, hollow chill supporting members in said drag and spaced apart, and a space between the chill supporting members filled with green sand, a baked sand core supported by the green sand, and a cope having a mold cavity above the green sand core and formed by a pattern and supported by the drag.

11. A mold comprising a drag and expansible chills resting upon the upper ends of

the chill supporting members and closing the same.

12. A mold comprising a drag, hollow chill supporting members in said drag, and 5 chills of the same contour and size as the upper end of the chill supporting members and resting thereon.

13. A mold comprising a drag, hollow chill supporting members in said drag and having 10 their upper ends flush with the upper edge of the drag and chills of the same contour as the upper ends of the supporting members and resting thereon.

14. A mold comprising a drag, chill supporting members in said drag, spaces between the chill supporting members filled 15 with green sand, chills supported by the upper ends of the chill supporting members and of the same contour as the upper ends of 20 the supporting members, a packed sand core resting upon the green sand and a cope resting upon the drag having a mold cavity surrounding the packed sand core.

In testimony whereof, I have signed this 25 specification.

WALTEN B. ROBE.
